(57) CLAIM

The ornamental design for a shoe bottom, substantially as shown and described.

DESCRIPTION

FIG. 1 is a top perspective view of a shoe bottom.

FIG. 2 is a bottom front right perspective view of the shoe bottom of FIG. 1.

FIG. 3 is a bottom front left perspective view of the shoe bottom of FIG. 1.

FIG. 4 is a bottom rear right perspective view of the shoe bottom of FIG. 1.

FIG. 5 is a bottom rear left perspective view of the shoe bottom of FIG. 1.

FIG. 6 is a front elevation view of the shoe bottom of FIG. 1.

FIG. 7 is a rear elevation view of the shoe bottom of FIG. 1.

FIG. 8 is a left side elevation view of the shoe bottom of FIG. 1.

FIG. 9 is a right side elevation view of the shoe bottom of FIG. 1.
